UNITED STATES PATENT OFFICE.

BARNETT D. GORDON, OF BOSTON, MASSACHUSETTS.

DESIGN FOR A STOCKING.

Application filed April 16, 1928. Serial No. 26,349. Term of patent 14 years.

To all whom it may concern:

Be it known that I, BARNETT D. GORDON, a citizen of the United States, residing at Boston, in the county of Suffolk and State of Massachusetts, have invented a new, original, and ornamental Design for Stockings, (Case A), of which the following is a specification, reference being had to the drawing forming a part thereof, of which,—

Figure 1 is a side elevation of a stocking showing my new design.

Figure 2 is a rear elevation of the same.

Figure 3 is an enlarged rear elevation of the heel portion of the stocking disclosed in Figure 2.

The dominant feature of this design resides in the shape and arrangement of the reinforced areas of the stocking above the heel as shown more particularly in Figure 3.

I claim:

The ornamental design for a stocking, as shown and described.

BARNETT D. GORDON.
